[57] CLAIM

The ornamental design for a golf tee, as shown and described.

DESCRIPTION

FIG. 1 is a perspective view of a golf tee showing my new design therefor;
FIG. 2 is a side elevational view;
FIG. 3 is a top plan view;
FIG. 4 is a bottom plan view;
FIG. 5 is a side elevational view opposite that of FIG. 2, the golf ball shown in broken outline is for purposes of environment and forms no part of the claimed design;
FIG. 6 is a perspective view of a golf tee showing my alternate design therefore;
FIG. 7 is a side elevational view;
FIG. 8 is a top plan view;
FIG. 9 is a bottom plan view; and,
FIG. 10 is a front elevational view, the rear elevational view being identical, and the golf ball shown in broken outline is for purposes of environment and forms no part of the claimed design.
